UNITED STATES PATENT OFFICE.

EDWARD J. HAWKINS, OF SOLVAY, NEW YORK.

MUSIC-LEAF TURNER.

1,211,579.

Specification of Letters Patent.

Patented Jan. 9, 1917.

Application filed October 4, 1915. Serial No. 53,981.

To all whom it may concern:

Be it known that I, EDWARD J. HAWKINS, a citizen of the United States, residing at Solvay, in the county of Onondaga and 5 State of New York, have invented certain new and useful Improvements in Music-Leaf Turners, of which the following is a specification.

The present invention relates to improved 10 music leaf turners designed for turning sheet music and operated by pedal mechanism.

The primary object of the invention is 15 the provision of a device of this character that is simple in construction and operation, but efficient in performing its functions.

The device is designed to be adjustable 20 for different conditions, in order that the music rack, of which the leaf-turner forms 25 a co-acting element, may be located in desired position above the key board of the piano or organ with which the device is utilized. By the utilization of pedal actuated instrumentalities, I am enabled to operate 30 the leaf turner and permit the player or artist to use the hands freely for playing purposes only. Provision also is made for turning back one or more leaves of music when desirable or necessary, without recourse 35 to the use of the hands, this being accomplished by an auxiliary pedal device.

The invention consists in certain novel combinations and arrangements of parts as 40 will be hereinafter more fully pointed out and claimed.

In the accompanying drawings I have 45 illustrated one complete example of the physical embodiment of my invention and a slight modification thereof, constructed according to the best mode I have so far devised for the application of the principles of my invention, but it will be understood that changes involving shapes and sizes of parts and colorable alterations are contemplated as within the scope of my claims.

Figure 1 is a side elevation of the device 50 embodying my invention, the separated parts of the device being closed up for convenience of illustration. Fig. 2 is a top plan view of Fig. 1. Fig. 3 is a front elevation of the device of Fig. 1, showing the pedal board and the music rack and leaf turner. Fig. 4 illustrates the three spring operated 55 sprocket wheels, one for each leaf turner when three are used. Fig. 5 is a side view of the spring wheel at the left in Fig. 4,

showing the spring in its casing and attached to the wheel shaft. Fig. 6 is a sectional view of the device of Fig. 5 on line 6-6. Fig. 7 is a sectional detail view of the bearing head of Fig. 3. Fig. 8 illustrates the three locking latches for their respective pedals, and the return pedal slide rod co-acting therewith. Fig. 9 shows a modified form of head for the leaf turner. Fig. 10 is a sectional view of the head of Fig. 9.

In the preferred embodiment of my invention as illustrated in the drawings I employ a music rack or board 1 of convenient and proper size to be located in suitable 70 position over the key board of the instrument, and suspended, vertically, by means of its bracket rod 2 which is supported in the bushing or head 3 of the swivel plate 4.

The board or rack 1 is equipped with the 75 usual bottom ledge 5 and the pairs of spring retaining clamps or clips 6 and 7 for holding the front and back pages of the music to the rack 1.

The rack may be supported from a suitable 80 portion of the piano, or if used as a portion of a music stand, it may be supported from a wall. In any event the swivel plate 4 is adjustably secured to the adjustable slide plate or extension 8 through the 85 pivot bolt 9 by which the swivel plate and slide plate are held, and the circular slot 10 in the plate 4 and set screw 11 which passes through the slot and is threaded in the end of the slide plate 8. By this connection it 90 will be seen that the music rack may be adjusted on the pivot point 9 in order to vary the inclination of the music rack with relation to the vertical.

The adjustable slide or extension plate 8 95 is perforated to accommodate two bolts or screws 12, 12' which are utilized to secure the extension plate 8 in desired relation with the complementary plate 13 which is also slotted as at 13' to accommodate the screws 100 12, 12' and overlaps the adjoining end of the plate 8. This arrangement of parts permits of an adjustment of the music rack toward or away from its supporting wall or other object, and enables the artist or musician to 105 adjust the rack to his wishes.

A further adjustment of the device is accomplished through the connection between the arm 13 and the bracket 14 by means of which the music rack is supported from a 110 stationary member as 15 by screws 16. The bracket 14 is fashioned with a swivel head

17 slotted at 18 and pivotally connected with the arm 13 by the bolt 19. Thus this swivel connection may co-act with the swivel connection at the free end of the extensible arms 13 and 8, and when in adjusted position the parts 13 and 17 may be secured together by the screw 20.

In the drawings I have illustrated the device as equipped with three leaf turners A, B, C, and it will be seen that these comprise angular arms each provided with the usual spring clamps 21, 22, provided with a release lever 22' to hold the leaf and insure its quick and proper movement when the leaf is turned. The leaf-turners are each fashioned with a shank or arm 23, 24, 25 respectively and these respective arms are fixed to bushings 26, 27, 28 of their sprocket wheels 29, 30, 31. These bushings and sprocket wheels are rotatable on the bracket rod or shaft 2 which is threaded at 2' for the clamp nuts 32 for holding the revolvable members on the shaft 2. Each of these sprocket wheels is revolved by a section of chain as 33, 34, 35 passed over the respective wheels and each chain has attached at its ends a cord or cable as 36, 37, 38, passing over guide pulleys 39 and 40, down to the pedal mechanism that is located in convenient position to be actuated by the foot of the musician.

Each pedal device includes a sprocket wheel as 41, 42, 43 and a section of chain as 44 is passed over each sprocket and connected to the ends of its individual cord or cable.

The sprockets 41, 42, 43 are spring wound *i. e.* each is equipped with a spring as 45, fastened at one end in its casing 46 and at 40 its other end to the shaft 47 of the sprocket wheels. Each of these shafts has a pedal as 48, 49, 50, formed each with a hook 51, for engaging the shaft and said pedals co-act with a pivoted latch 53, 54 and 55, which 45 have the cam face 52 and are pivoted at 56 on the board 57, the springs 56' being provided for retaining the latches in normal position. This cover board 57 is slotted so 50 that the hooked ends of the pedals may protrude from the interior, and it will be apparent that by depressing the pedal 48 for instance by foot power, the cam face 52 will be forced aside to allow the pedal to pass below the straight underside of the latch 53, 55 when the spring 56' will return the latch and thus retain the pedal in downward or depressed position, this depressing of the pedal revolves the sprocket wheel 41, winding or tightening the spring 45, which 60 returns the parts to normal position as is herein-after set forth, and through the chain and cord connections the leaf turner is folded or swung over to turn the leaf of music. The 65 three pedals are operated successively and their individual actions are similar.

A fourth pedal is employed to return the latches to normal position. This pedal is pivoted on the cover board 57 at 59 and connected to a slide bar 60 at 61. The slide bar is movable in bearings 62 and is formed with 70 a series of three lugs 63 adapted to impinge against the lower end of the latches. When the pedal 58 is pressed down, the movement of the slide bar 60 to the right, see Fig. 8, moves all of the latches on their pivots 56, 75 releasing the pedals 48, 49 and 50 and allowing the springs 45 to unwind, revolving the sprocket wheels 41, 42 and 43 backward, and through the chain and cord connections return the leaf turners to normal position, and 80 when pressure is removed from the pedal the spring 60' restores the latches to their normal position. Each latch is provided with an individual pin as 64 by means of which it may be swung on its pivot and re-turned to normal position.

In the modified forms of the invention in Figs. 9 and 10 the arms 25', 24', 23' are arranged below the head 3' instead of above the head, to make a more compact arrangement of parts which is sometimes desirable.

What I claim is:—

1. In a music leaf turner including a music rack, the combination of a leaf holding element rotatably supported thereon, a sprocket wheel and shaft operatively connected with the leaf holding element, a sprocket chain on the wheel having a cord attached to its ends, a spring actuated sprocket wheel and a supporting shaft therefor having a pedal rigidly connected thereto, a second sprocket chain, and means for releasably holding said pedal, said cord being connected to the ends of the second sprocket chain.

2. The combination with a rotatably supported music leaf turning element, of a sprocket wheel and chain operatively connected thereto, a second sprocket wheel and chain operatively connected to the first sprocket wheel and chain, a supporting shaft for the second wheel and a coiled spring for rotating said wheel, means for rotating the wheel against the tension of the spring, and a latch for holding the wheel from operation, a second pedal, and means connected therewith to release said latch.

3. The combination with a rotatable leaf turning element, of a spring wound wheel operatively connected thereto, a shaft for said wheel carrying a pedal, a latch for holding said pedal in inoperative position, and means for restoring said latch to operative position.

4. The combination with a rotatable leaf turning element including a spring wound operating wheel, of a shaft for said wheel and a pedal carried thereby, a latch for holding said pedal in inoperative position, a second pedal and means connected with

said second pedal for restoring said latch to operative position when released by movement of the second pedal, said means consisting of a spring actuated slide bar connected with the second named pedal having a lug thereon adapted to impinge against the lower end of the latch.

In testimony whereof I affix my signature in the presence of two witnesses.

EDWARD J. HAWKINS.
